UNITED STATES PATENT OFFICE.

JOHN W. KENNEDY, OF ROCHESTER, NEW YORK.

FOLDING WARDROBE-RACK.

No. 822,133.

Specification of Letters Patent.

Patented May 29, 1906.

Application filed January 31, 1906. Serial No. 298,812.

To all whom it may concern:

Be it known that I, JOHN W. KENNEDY, a citizen of the United States, residing at Rochester, in the county of Monroe and State of New York, have invented certain new and useful Improvements in Folding Wardrobe-Racks; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in folding wardrobe-racks; and the object of the invention is to produce a simple and efficient device of this character comprising a folding rack which when opened out for use is adapted to be securely held in the corner of a room without the use of nails or screws and affording means for holding a suitable drapery.

The invention comprises various details of construction and combinations and arrangements of parts which will be hereinafter fully described and then specifically defined in the appended claims.

I illustrate my invention in the accompanying drawings, in which—

Figure 1 is a perspective view showing the application of my improved folding wardrobe-rack adjusted for use. Fig. 2 is a view showing the rack folded. Fig. 3 is a top plan view showing the positions that the parts assume when the rack is about to be fastened to the walls of a room. Fig. 4 is a detail view of one of the spur-plates upon the rack; and Fig. 5 is a detail view showing the manner of holding the connecting pivotal cross-pieces in alinement with each other, thus insuring the holding of the rack securely to the walls of a room.

Reference now being had to the details of the drawings by letter, A and A' designate two strips having recessed ends, and B is a pivotal pin connecting said strips, it being noted that the opposite faces of said strips are recessed or cut away upon opposite faces, whereby when the two strips are in alinement the opposite faces of the two strips will be in parallel planes. Pivotaly mounted upon pins C, which are held in the bifurcated ends of the strips A and A', are the pieces D. E E designate arms having hinge connec-

tion with said pieces D and are adapted to fold back upon the respective strips D, to which they are fastened. Secured to the outer faces of the pieces D are the spur-plates F, which are provided to engage the walls of a room in order to securely hold the folding wardrobe-rack extended, as clearly shown in the drawings.

In order to lock the two pivotal pieces A and A' in alinement with each other, I provide the ordinary hooks N, which when turned in the direction shown in dotted lines in the drawings will allow the two pieces to turn freely upon their pivotal pins; but when the hooks are held in the position shown in solid lines it will be observed that the lower portion of the hook upon corresponding sides of the strips will prevent the latter from turning in one direction, while the other hook upon the opposite sides will prevent the strips from being turned in the opposite direction, thereby holding the same in alinement.

The outer ends of the arms E have apertures E' therein, in which are adapted to be inserted angled ends O of the drapery-supporting rods O', the meeting ends of said drapery-rods being connected together by a union or other suitable connection, and upon which drapery-rods draperies may be hung.

Fastened to the upper faces of the strips D are the screw-eyes T, being provided for the purpose of holding strings connecting the same with the angled ends of the drapery-supporting rods, whereby a cloth cover shirred upon the strings may be hung, thereby completing the clothes-press idea and forming a suitable closure for the invention.

In adjusting the rack in place the two pieces D, with the hinged arms opened out, are placed against the adjacent walls in the corner of a room, and the pivotal strips connecting said pieces are tilted at angles to each other and afterward brought into alinement, forming a toggle-link means for forcing the spurs upon the outer faces of the strips securely in the walls of the room at right angles to each other, after which the hooks before described may be turned to hold the two strips in alinement, thereby insuring the holding of the wardrobe-rack without the necessity of screws, nails, or other fastening means, as will be readily understood.

If preferred, a shelf may be placed upon the upper edges of the strips E and E instead

of the cloth covering, thereby affording means for supporting articles.

What I claim is—

1. A folding wardrobe-rack comprising strips which are pivoted together, means for holding said strips in alinement with each other, arm-supporting pieces pivoted to the outer ends of said strips, and spur-plates secured to the faces of said pieces, as set forth.
2. A folding wardrobe-rack comprising strips which are pivoted together, means for holding the strips in alinement with each other, pieces pivoted in the recessed ends of said strips, folding arms mounted upon said pieces, and spur-plates upon the outer faces of said pieces, as set forth.
3. A folding wardrobe-rack comprising strips which are pivoted together, means for holding said strips in alinement with each other, pieces pivoted in the recessed ends of said strips, folding arms mounted upon said pieces, and drapery-supporting rods having angled ends mounted in apertures in said folding arms, as set forth.
4. A folding wardrobe-rack comprising two strips having their inner ends recessed, a pivotal pin connecting the inner ends of said strips, hooks, one mounted in each of said strips and adapted to be turned in such position as to hold the strips in alinement with

each other, pieces pivoted in the recessed ends of said strips, and folding arms hinged to said pieces, as set forth.

5. A folding wardrobe-rack comprising horizontally - movable toggle - link strips which are pivoted together, wall-engaging pieces pivotally connected to the outer ends of said strips, spur-plates upon the faces of said pieces, said strips being adapted, when in alinement, to hold said spur-plates in engagement with the walls of a room, to support the rack, as set forth.

6. A folding wardrobe-rack comprising horizontally - movable toggle-link strips which are pivoted together, wall-engaging pieces pivotally connected to the outer ends of said strips, spur-plates upon the faces of said pieces, said strips being adapted, when in alinement, to hold said spur-plates in engagement with the walls of a room, to support the rack, and means for holding the strips in alinement with each other, as set forth.

In testimony whereof I hereunto affix my signature in the presence of two witnesses.

JOHN W. KENNEDY.
